UNITED STATES PATENT OFFICE.

EDWARD J. GODFREY, OF NAUGATUCK, CONNECTICUT, ASSIGNOR TO THE GOODYEAR'S METALLIC RUBBER SHOE COMPANY, A CORPORATION OF CONNECTICUT.

METHOD OF MAKING BRIEF CASES.

Application filed July 12, 1920. Serial No. 395,651.

This invention relates to a method of making brief cases, and more particularly to a case made of built-up plies of vulcanizable material.

5 Brief cases made of good quality leather, owing to the high price of the material, have reached a price which is almost prohibitive. Cases made of a cheaper grade of leather are lacking in the durability, strength, and 10 appearance of the higher priced article. Attempts have also been made to make such cases of imitation or substitute leather, but these articles are also lacking in durability and appearance. Moreover, owing to the 15 high price of good quality thread, a cheaper grade is frequently used in sewing the brief cases, and as a consequence they readily come apart at the seams where subjected to abrasion, necessitating frequent repair. In 20 fact, abrasion causes this trouble even where a good quality of thread has been used. In addition, all such cases, whether made of leather or an imitation, are not waterproof.

An object of my invention is to provide 25 a light, strong, durable and inexpensive brief case of good appearance.

Another object is to provide a seamless and waterproof brief case.

Still another object is to provide a brief 30 case of vulcanizable material, the parts of which are integrally united by vulcanization.

A further object is to provide a simple and rapid method of making the brief cases.

For a full and complete disclosure of the 35 invention reference is had to the accompanying specification and drawings, in which latter,

Fig. 1 is a diagrammatic section through the brief case from front to rear, illustrating 40 the manner in which it is built up on forms;

Fig. 2 is a broken away perspective illustrating one of the forms at an initial stage in the method;

Fig. 3 is a similar view of another form;

Fig. 4 is an enlarged detail section broken 45 apart illustrating the front wall construction;

Fig. 5 is a similar section illustrating the partition construction;

Fig. 6 is a broken view showing the side 50 wall in section, and

Fig. 7 is a front view of the completed brief case.

Referring to the drawings, the numerals 1 and 2 are applied to different forms used in building up the brief cases. For a case of given length and width the forms 1 are all of the same size, while the form 2 is of the same width and thickness as forms 1, but is of greater length. In building up the

case one or more of the forms 1 are used, depending on the number of compartments desired in the finished case, while but one of the forms 2 is used, the latter being the form around which the rear compartment

and flap of the case are constructed. A strip 3 of frictioned lining material is stretched around the bottom and side edges of each form 1 and temporarily tacked down as shown at 4, and a similar strip 3 of about

the same length is stretched across the bottom of a form 2 and part way up the side thereof and temporarily secured by tacks 5, the frictioned surface of the strip being turned outward in each case. The required

number of partitions is next made up, each partition being formed of a sheet of stiff paper 6 of substantially the same area as the form 1, a sheet 7 of the frictioned lining material being cemented to the opposite

sides of the paper sheet 6 with the fabric side 8 turned out and the frictioned side 9 next to the paper as shown in Fig. 5. The side and bottom edges of the sheets 7 project beyond the paper for a purpose to be

presently explained. The required number 85 of forms 1 are then superposed on a single one of the forms 2 as shown in Fig. 1 with a partition interposed between each of the forms. A reinforced front wall lining is

placed on the exposed wall of the end form 1, said lining comprising a sheet of paper 6 having cemented to one side only thereof a sheet 7 of the frictioned lining material. The rear wall lining of the case, which is

also to form the lining of the flap, is formed 90 in a similar manner to the front wall lining by superposing on the exposed surface of the form 2 a sheet of paper 11 having cemented to one side thereof a sheet 12 of the frictioned lining material. The bottom and

side edges of the lining material of the front wall project slightly beyond the paper as in the case of the partitions, and the bottom edge of the lining sheet 12 and its side edges

100 up to the top of the forms 1 also project

beyond the sheet of paper 11. The bottom and side edges of the sheets 7 and 12 are next turned over and rolled down upon the strips 3 as shown at 10 in Fig. 1, which 5 completes the assembly of the lining.

An outer covering sheet 13 of wear resisting vulcanizable material is provided for the bottom and side walls of the assembled forms. This sheet is of slightly greater 10 width than the thickness of the assembled forms and is of a length sufficient to extend across the bottom wall and up the side walls to a point slightly above the tops of the forms 1. This material 15 is formed of twill or other suitable fabric 14, coated on the inside with rubber 15 and on the outside with a wear resisting rubber composition 16 (see Figs. 4 to 6), and may be suitably embossed to simulate any desired 20 grain. Desirable wear resisting qualities in the rubber composition 16 are toughness, resistance to abrasion, and good aging, and in the making of the bags a composition having the desired qualities may be readily 25 mixed in a manner well known to those expert in the art, the precise ingredients of the composition 16 forming no part of the invention. The sheet 13 is cemented prior to its application to the forms and after 30 stretching around the same is rolled down on the strips 3 and edges 10 and its projecting side and bottom edge portion 17 turned over and cemented against the respective front and back wall paper sheets 6 and 11. 35 The front wall sheet 18 of wear resisting material is next applied, this sheet first having had the lower portion 19 of the lock members riveted thereto through an inner reinforcement 20, the reinforcement being 40 covered by a strip of friction stock 21, as shown in Fig. 1. The sheet 18 as cut from the stock is of somewhat greater area than the form 1 and prior to the application of said sheet its side and bottom edges are doubled under at 22 so that when the sheet is 45 cemented to the paper 6 said doubled under edges 22 are in line with the turned over edges 17 and are cemented thereto. The rear wall 23 of wear resisting material is 50 next cemented to the paper sheet 11 in a manner similar to the front wall. This sheet is provided with a projecting portion 24 at its bottom and around its sides to a height equal to that of the form 1, and this 55 projecting portion is doubled under and cemented to the turned over portion 17 when the sheet 23 is cemented to the paper 11. Prior to the application of the sheet 23 its upper portion, which is to form the flap, is 60 provided with a handle 25 riveted through the sheet to an inner reinforcement plate 26, which latter is covered with a strip of friction stock 27. Corner reinforcements 28 of high grade gum stock are next cemented on as shown in Fig. 7. The tacks 4 and

5 are then withdrawn and the forms 1 and 2 removed. Binding strips 29 of the wear resisting material are next applied to the top edge of the front wall and partitions and also to the top and side edges of the flap 70 portion of the rear wall, as shown in Figs. 4 to 7. The portions of the side wall 13 projecting above the partitions are next slit opposite each partition and each projecting portion 30 and underlying end of strip 3 75 turned in between adjacent partitions and cemented and rolled down as shown in Fig. 6. The upper lock portions 31 are next riveted to the edges of the flap, which completes the building operation and the brief cases 80 are then ready to be varnished and cured. The forms are next removed and the brief case is placed in a suitable mold and cured.

In place of the spaced locks as shown in Fig. 7 a central lock and side straps may be 85 substituted, the straps in this case being secured to the rear wall and extending up over the flap, and the buckles being secured to the front of the wall in the usual manner. If desired, a heavier grade lining may be 90 used and the paper reinforcements omitted, or the upper edges only of the partitions may be reinforced.

Various other changes may be made, which will readily be suggested to one 95 skilled in the art by the present disclosure, without departing from the scope of the appended claims.

It will be seen that by my method of construction a brief case is produced which is 100 strong, light, and of good appearance, which has no stitched seams to open up, and the walls of which are entirely waterproof.

Having thus described my invention what I claim and desire to protect by Letters Patent is:

1. A method of making brief cases which comprises, covering a form with vulcanizable lining material, superposing a plurality of the covered forms, covering the lining material on the edges of the forms with an outer ply of wear resisting vulcanizable material, covering the lining material on the exterior walls of the end forms with outer plies of the wear resisting material, withdrawing the forms, and vulcanizing the case into an integrally united article.

2. A method of making brief cases which comprises, covering the bottom and side edges of a plurality of forms with a vulcanizable lining material, superposing the forms with sheets of vulcanizable lining material interposed between them, covering the outside walls of the end forms with sheets of the lining material, joining all of said sheets to the edge covering material, applying a sheet of wear resisting vulcanizable material to the edge covering material, applying sheets of the wear resisting material to said second named sheets, removing the

forms, and vulcanizing into an integral whole.

3. A method of making brief cases which comprises covering the edges of flat rectangular forms with strips of vulcanizable material, superposing a plurality of said forms with double plies of vulcanizable material between their adjacent surfaces and single plies on the end surfaces, one end form being 10 of greater length, lapping over said plies on adjacent strips, covering all of said strips with an edge sheet of wear resisting vulcanizable material, covering the end single plies with wear resisting material, removing the 15 forms, and vulcanizing the article.

4. A method of making brief cases which comprises building up connected inner partitions and end walls of vulcanizable material, one of said end walls being of greater 20 length to form a flap, providing the flap with a handle and the flap and other end wall with complementary securing means,

and vulcanizing the parts into an integrally united article.

5. A method of making brief cases which 25 comprises building up on forms a plurality of spaced plies of vulcanizable material, the outer ply at one end projecting beyond the others to form a flap, joining the spaced side and bottom edges of the plies by edge strips, 30 covering said edge strips with a sheet of wear resisting vulcanizable material, covering the outer sides of the end plies with end sheets of the wear resisting material and lapsing them over the edges of the first 35 sheet, attaching coacting securing means to the end sheets and a handle to the projecting flap portion of one end sheet, removing the forms, and vulcanizing the parts into a 40 seamless, waterproof article.

Signed at Naugatuck this 7th day of July, 1920.

EDWARD J. GODFREY.
